UNITED STATES PATENT OFFICE.

GEORGE P. MALLORY, OF PHILADELPHIA, PENNSYLVANIA, ASSIGNOR TO SANITARY PRODUCTS CORPORATION OF AMERICA, OF PHILADELPHIA, PENNSYLVANIA, A CORPORATION OF VIRGINIA.

FORK DIES.

Application filed April 11, 1922. Serial No. 551,505.

To all whom it may concern:

Be it known that I, GEORGE P. MALLORY, a citizen of the United States, residing at Philadelphia, county of Philadelphia, State of Pennsylvania, have invented a certain new and useful Improvement in Fork Dies, of which the following is a specification, reference being had therein to the accompanying drawings.

- 10 This invention relates to machines for forming articles from sheet material and especially, although not exclusively, to die presses for forming forks from paper or similar plastic or semi-plastic material.
- 15 The invention has for an object to provide an improved die for use in forming, from sheet material, articles of such shape as to cause them to tend to adhere to the die after their formation, which die, while 20 capable of performing its shaping function in as efficient and reliable a manner as a solid die, is so constructed as automatically to eject the articles formed thereby without the use of separate ejectors or knockout pins 25 of the character usually employed for this purpose.

In Letters Patent No. 1,378,707, granted to me May 17, 1921, is shown and described a pair of blanking and shaping dies for 30 forming paper spoons, said dies comprising handle and bowl forming portions, the handle forming portions being of such a character as to clamp the material along the line of the handle prior to the shaping operation, so as to center the same and insure the accurate shaping of the spoon, and the clamping portion of one of the dies including a movable member adapted also to act as a knockout or ejector. When the dies 35 are separated this movable member is projected from the body of the die and is held in a projected position during the closing of the die and until forced into a retracted position by the thrust of the cooperating die during the shaping operation, so as to 40 engage and clamp the material prior to the engagement thereof with any other part of the corresponding die.

The present invention has for a more particular object the adaptation of dies of the above type to the purpose of making forks. By reason of the fact that the prongs of the fork do not strip readily from the blanking die, special provision is necessary for 45 ejecting the same. In accordance with the

invention, the die is so constructed as effectively to accomplish this result, while at the same time permitting all shaping portions of the die to remain out of engagement with the material until the latter is 60 firmly engaged by the clamping member above referred to.

The foregoing and other objects of the invention, together with means whereby the same may be carried into effect, will best be 65 understood from the following description of one form or embodiment thereof illustrated in the accompanying drawings, in which:

Fig. 1 is a front elevation of a die press 70 embodying the invention.

Fig. 2 is an enlarged vertical transverse section of the dies, showing the same in their separated position.

Fig. 3 is a vertical longitudinal section of 75 the dies, showing them in their closed position with a completed fork between the same.

Fig. 4 is a plan view, and Fig. 5 is an edge view of a completed fork of the type 80 which the dies shown are adapted to make.

Fig. 6 is a detail bottom plan view of the blanking out portion of the upper die.

With certain exceptions hereinafter more fully described, the general arrangement 85 may be substantially as shown in Letters Patent No. 1,378,707, above referred to, to which reference may be had for a further description of certain details not described at length herein. As shown in said prior 90 patent, the frame of the press comprises a base 10 (see Figure 1) with uprights 11 in which is journalled a crank shaft 12, which may be operated by power applied thereto in any suitable way, as through a belt 95 pulley 75. The crank shaft 12 carries a crank arm 13 connected by a pitman 14 with a crosshead or ram 15 which reciprocates in suitable guides 16 carried by the uprights 11. The crosshead or ram carries the movable dies 17 which cooperate with fixed dies 18 carried by the base 10. The cooperating dies 17 and 18 may be of any desired 100 number, two oppositely disposed pairs being preferably employed, as in said prior 105 patent.

The movable dies 17 are mounted in an upper die carrier 19 secured to an upper die plate 20 attached to the ram 15. The upper die plate 20 is guided on posts 21 110

rising from a lower die plate 22 resting on the base 10. Secured to the lower die plate 22 is a lower die carrier 26 in which the fixed dies 18 are mounted.

5 The dies as herein shown are designed to blank out and shape, from a web of paper or other sheet material A (Figure 1), forks of the form illustrated in Figures 4 and 5. Each of said forks comprises a slightly 10 dished head B formed with prongs *a*, and a handle C having a shank portion *b* and a tip *c*. The shank portion *b* of the handle is formed with downwardly bent edges to constitute a longitudinal stiffening rib or 15 corrugation which, with slightly modified cross-section, extends into the tip portion *c* and also into the central prong *a*, the remaining prongs being formed with similar stiffening ribs.

20 Each die 17 comprises a cutting or blanking out portion 23, a head shaping portion 28, and a handle shaping portion including two parallel members or plates 29 fixed to the portion 23 by pins 30 and a member or 25 plate 31 movably mounted between the fixed members 29. The members 31 are attached to a common stem 32 having a head 33 engaging openings in said plates, and a shank which extends upwardly through a 30 sleeve 34 projecting from the back or top of the die plate 20 and into an opening in the ram 15. Within the sleeve 34 is a yielding clamp 35 which frictionally engages the stem 32 and holds the same in 35 any position into which it is moved. The upward movement of the members 31 is limited by adjustable stops 36.

Each die 18 comprises a blanking out portion cooperating with the blanking out portion 23 of the die 17 and surrounded by a 40 spring supported stripper plate 24. The blanking out portion of each of the dies 18 constitutes also, in substance, the shaping portion thereof and comprises a head 45 shaping part or member 25, a handle tip shaping part or member 27, said members 25 and 27 being secured to the die carrier 26, fixed handle shank cutting members 37 supported by the die carrier 26, and a handle shank shaping member 38 mounted for 50 a limited movement in the carrier 26 and between the members 37, said member 38 being supported by springs 39.

Except as hereinafter pointed out, the 55 construction, arrangement, and operation of the parts above referred to may be substantially as more fully described in my prior patent above referred to. As the ram 15 rises with the movable dies 17, the stem 32 60 engages a fixed stop in the form of an adjustable knock-out bar 40 carried by the guides 16 and extending through an opening in the ram, thereby moving the members or plates 31 into the projected position 65 shown in Figure 2. Said members 31 re-

main in this position during the descent of the dies 17, so as to engage and clamp the stock against the members 38 during the dieing out operation, the members 38 being forced back against the springs 39 to the 70 limit of this movement. Thereafter, as the dies 17 continue to descend, the members 31 are forced back by the thrust of the stationary die members 38, so that the members 29 bind the material over the members 27 75 and 38 to form the handles C, while the members 25 and 28 cooperate to shape the heads B. As the upper dies rise, the springs 39 cause the members 38 to lift the completed articles out of the lower die, and said articles are carried up by the upper dies until the stem 32 engages the knockout bar 40, whereupon the members 31, which during the ascent of the dies have been held in retracted position by the clamp 35, are 80 projected outwardly to eject said articles. 85

In the construction shown, the blanking-out portions 23 and 25 of the upper and lower dies respectively are so formed as to cut out the prongs *a* of the fork head B, 90 while the shaping portions 28 and 25 respectively of said dies are of such a form as to shape said prongs and the stiffening ribs therein. It is found, however, that the nature of the prongs *a* is such as to cause 95 them to tend to adhere to the corresponding parts *a'* (see Figure 6) of the blanking-out portion 23 of the upper die, so that the forks are not properly ejected by the members 31 as above explained. In accordance, therefore, with the present invention, the head shaping portion 28 of the upper or movable die is not rigidly secured to the die carrier 19 but is mounted thereon for movement into either its operative or retracted position, or into a projected or ejecting position. To this end the member 28 is secured to a stem 41 which extends upwardly through the die plate 20 and is guided for longitudinal movement therein. Said member 28, during the forming operation, rests solidly against the die carrier 19 and forms, in effect, a rigid portion of the die, but when said die rises the stem 41 engages the knockout bar 40, causing 100 said member 28 to be projected outwardly and thereby stripping the prongs *a* from the cutter 23. 105

In order, however, to permit the members 31 to perform their clamping function as 110 above explained, it is necessary that said members engage the stock before the other forming portions of the die, and it is consequently necessary that the member 28 be held in its retracted position during the descent of the die. To this end, the stems 41 are formed with heads 42 between which and the upper face of the die plate 20 are interpositioned springs 43 which normally hold 115 the die members 28 in their retracted posi- 120

tions, said springs, however, yielding to permit said members to be projected outwardly by the engagement of the ends of the stems 41 with the knockout bar 40, but acting to return said members to normal position as soon as permitted by disengagement of said heads from said bar.

It will thus be seen that, so far as the head shaping portion of the upper die is concerned, said die is, to all intents and purposes, a solid die, its parts being so constructed as normally to occupy their operative positions with respect to one another in the same manner as the parts of a solid die, but being adapted, upon the separation of the dies, to release and eject the formed articles notwithstanding the irregular shape of the latter or the tendency thereof to cling to the die.

20 What I claim is:

1. In a machine for forming articles from sheet material, a pair of relatively movable dies having cooperating shaping portions, the shaping portion of one of said dies including a part which is movable with respect to the remainder of said shaping portion, means tending normally to hold said movable part in a retracted or operative position with respect to the other parts of the shaping portion of said die, and means for projecting said part out of operative position, when said dies are separated, to eject said articles.

2. In a machine for forming articles from sheet material, fixed and movable dies having cooperating shaping portions, means for reciprocating said movable die, the shaping portion of said movable die including a movable part having a stem extending through the rear of said die, a spring cooperating with said stem to hold said movable part normally in a retracted or operative position in said movable die, and a fixed stop adapted when said movable die is moved away from said fixed die to engage said stem and project said movable part out of operative position to eject said articles.

3. In a machine for forming forks from sheet material, a pair of relatively movable dies having cooperating portions for shaping the handles and prongs of the forks, the prong shaping portion of one of said dies being separate from the remainder of said die and movable with respect thereto, means for normally holding said prong shaping portion in a retracted or operative position in said die, and means for projecting said part out of operative position when said dies are separated to release and eject the prongs of a completed fork.

4. In a machine for forming forks from sheet material, fixed and movable dies having cooperating portions for shaping the handles and prongs of the forks, means for reciprocating said movable die, the prong

shaping portion of said movable die being separate from the handle shaping portion thereof and movable with respect thereto, a spring for normally holding said prong shaping portion in a retracted or operative position in said movable die, and a fixed stop adapted when said movable die is moved away from said fixed die to engage said prong shaping portion and project the same out of operative position to release and eject the prongs of a completed fork.

5. In a machine for forming articles from sheet material, a pair of relatively movable dies having cooperating shaping portions, the shaping portion of one of said dies comprising a plurality of relatively movable parts, each of said parts being adapted to occupy a retracted or operative position with respect to said die or a projected or ejecting position, one of said parts, when in projected position, acting also to clamp the material against the cooperating die prior to the shaping operation and being free to remain in said projected position when moved thereinto, means for moving both of said parts into projected position when said dies are separated, and means to move the other of said parts into retracted or operative position when permitted by said projecting means.

6. In a machine for forming articles from sheet material, fixed and movable dies having cooperating shaping portions, the shaping portion of said movable die comprising fixed and movable parts, each of said movable parts being adapted to occupy a retracted or operative position with respect to said fixed parts or a projected or ejecting position, means for holding one of said parts in either of said positions into which it is moved, said last named part, when in projected position, acting also to clamp the material against the fixed die prior to the shaping operation and being moved by said fixed die into retracted position during said shaping operation, a stop adapted when said movable die is moved away from said fixed die to move both of said movable parts into projected position, and a spring for moving the other of said parts into retracted position when disengaged from said stop.

7. In a machine for forming forks from sheet material, a pair of relatively movable dies having cooperating portions for shaping the handles and prongs of the forks, the handle shaping portion of one of said dies having a movable part, and the prong shaping portion of said die comprising another separate movable part, each of said movable parts being adapted to occupy either a retracted or a projected position with respect to said die, the movable part of said handle shaping portion, when in projected position, acting to clamp the ma-

terial against the cooperating die prior to the shaping operation, and being free to remain in said projected position when moved thereto until forced back into retracted position by the thrust of said cooperating die during the closing of the dies, means for moving both of said movable parts into projected position when said dies are separated, and means for moving said movable prong shaping portion into retracted position when permitted by said projecting means.

8. In a machine for forming forks from sheet material, fixed and movable dies having cooperating portions for shaping the handles and prongs of the forks, the handle shaping portion of said movable die comprising two fixed parts and a movable part between said fixed parts, and the prong shaping portion of said movable die comprising another separately movable part, each of said movable parts having a stem extending through the rear of said movable

die, and each being adapted to occupy either a retracted or a projected position with respect to said movable die, the movable part of said handle shaping portion, when in projected position, acting to clamp the material against the cooperating die prior to the shaping operation, a yielding clamp cooperating with the stem of said last named movable part to hold the same in either its projected or its retracted position when moved thereto, a stop adapted when said movable die is moved away from said fixed die, to be engaged by the stems of both of said movable parts and thereby move said parts into projected position, and a spring cooperating with the stem of said prong shaping part to move the same into retracted position when said stem is disengaged from said stop.

In testimony whereof I affix my signature.

GEORGE P. MALLORY.
